Inventor:
Max Green
J. G. Geisler
by Atty?

UNITED STATES PATENT OFFICE.

MAX GREEN, OF PORTLAND, OREGON.

BATHING SUIT.

Application filed June 21, 1922. Serial No. 569,934.

To all whom it may concern:

Be it known that I, MAX GREEN, a citizen of the Republic of Poland, and a resident of Portland, county of Multnomah, and State of Oregon, have invented a certain new and useful Improvement in Bathing Suits, of which the following is a specification.

The object of my invention is to provide a means for holding the skirts of a one piece bathing suit in place concealing the trunks.

A further object is to incorporate a support in a bathing suit which is effective but is comfortable and allows freedom of movement.

16 A further and incidental object is so to construct a one piece bathing suit so as to eliminate all possible objections to the suit from the standpoint of modesty.

Speed swimmers and divers have long objected to skirts on their bathing suits as they have noticed that the loose skirts impede their movements and detract from their skill. The skirts of a necessity have to be made full and water and continued use soon destroy their inherent elasticity. This causes the skirt to float out from the body when in the water and hampers the movements of the wearer.

The result is unsightly also when the bather leaves the water because the skirt usually has crept up about the hips and discloses the trunks underneath. This has caused the bathing supervisors to frown upon this type of suit on the grounds of modesty, and in some cases they have ruled this type of suit from the beaches.

The connecting strap is made a substantial width and of an elastic material so that it can fit snugly to the body and still not irritate or bind. If this strap is made of knitted material the ribs are placed transverse of the strap so as to utilize the elasticity of this type of fabric.

These and other objects are illustrated in the accompanying drawings, in which:

Fig. 1 is a view of a bathing suit shown in outline and shows my invention partly in dotted lines;

Fig. 2 is a fragmentary perspective view showing the supporting strap in position and shows that the strap is made with the ribs running transversely;

Fig. 3 is a developed longitudinal section and shows how the supporting strap hugs the body and thus prevents the skirt of the suit from moving from its normal position;

Fig. 4 is a fragmentary perspective view of a part of a bathing suit and has parts broken away to show the buttoned supporting strap in position; and

Fig. 5 is a fragmentary perspective view of a modified type of support inasmuch as the ends are widened so as to provide a wider connection to the suit.

My invention relates particularly to a one piece bathing suit *a* which has an attached skirt *b*, but is equally adapted to two-piece suits. The bottom of the suit is made into leg portions *c* which are normally covered substantially by the skirt *b*. The skirt *b* is fastened to the middle of the suit *a* by the seam *d*. It is loose on its lower edge *b'* and is only held in place by the inherent elasticity of the fabric of which it is made. When this fabric loses this elasticity by continued use or otherwise the skirt does not have any restraining portion to hold it in position.

I have fastened the strap *e* to the front and back portions of the skirt *b* and have so positioned the strap between the leg portions *c*. The crotch between the leg portions limits the upward movement of this strap and thus the skirts are held from climbing up. It has been found that this strap also prevents shrinking of the suit slightly.

As can be seen in Fig. 3, the strap also pulls the skirt closer to the body and this will minimize the frictional drag of the suit in the water. As has been heretofore stated, it will also eliminate any hampering of a swimmer's stroke because of the entangling of the skirt with the arms.

The supporting strap may have buttons *f* placed thereon and thus can be detached.

The supporting strap should be fastened by a substantial broad surface so as not to distort the lines of the suit. This feature is accentuated in Fig. 5 in which the ends *g* of the strap *e'* are slightly wider than the middle so as to present slightly more width for attaching to the suit.

I claim:

A bathing suit, comprising a trunk hose,

a skirt overlying the hose and terminating at its lower edge a short distance below the crotch portion of the hose, and a strap secured at its respective ends to the skirt portion immediately adjacent the free edge of the latter, said strap extending between the leg portions of the trunk hose and substan-

tially in contact with the crotch portion thereof, whereby to maintain a substantially constant relation between the lower edge of 10 the skirt and the trunk hose and prevent such lower skirt edge from riding up over the trunk hose.

MAX GREEN.
